US00D916833S

(12) **United States Design Patent** (10) Patent No.: **US D916,833 S**
 Kennerly et al. (45) Date of Patent: **** Apr. 20, 2021**

(54) **DISPLAY SCREEN OF A COMPUTER WITH A GRAPHICAL USER INTERFACE WITH OBJECT TRACKING GAME**

(71) Applicant: **LUMOS LABS, INC.**, San Francisco, CA (US)

(72) Inventors: **David Ethan Kennerly**, San Francisco, CA (US); **Benjamin Lee Ahroni**, San Francisco, CA (US); **Aaron Kaluszka**, Hayward, CA (US)

(73) Assignee: **LUMOS LABS, INC.**, San Francisco, CA (US)

(**) Term: **15 Years**

(21) Appl. No.: **29/702,667**

(22) Filed: **Aug. 21, 2019**

Related U.S. Application Data

(63) Continuation of application No. 29/588,353, filed on Dec. 20, 2016, now Pat. No. Des. 857,707, which is a continuation of application No. 14/338,165, filed on Jul. 22, 2014, now abandoned.
